UNITED STATES PATENT OFFICE.

OTTO JAEGER, OF NORRISTOWN, PENNSYLVANIA.

COIN-CONTROLLED DEVICE.

1,227,150.

Specification of Letters Patent. Patented May 22, 1917.

Application filed April 11, 1913. Serial No. 760,382.

To all whom it may concern:

Be it known that I, OTTO JAEGER, of Norristown, in the county of Montgomery and State of Pennsylvania, have invented certain new and useful Improvements in Coin-Controlled Devices, whereof the following is a specification, reference being had to the accompanying drawings.

The invention relates more particularly to 10 a coin controlled device used for the vending of liquids, although it is to be understood that the coin controlled device may be used in other connections.

An object of the invention is to provide 15 a coin controlled device wherein a coin may be used for causing a reciprocating member to move a second reciprocating member which in turn is manually operated for the purpose of actuating certain devices.

20 A further object of the invention is to provide a coin controlled device wherein a coin may be utilized in connection with a reciprocating carriage for causing a second reciprocating carriage to be brought into op-

25 erative relation with a manually operated plate so that it may be positively actuated thereby, and wherein said carriages may be automatically returned to a normal position when the manually operated plate is released. These and other objects will in part 30 be obvious, and will in part be hereinafter more fully disclosed.

In the drawings which show by way of illustration one embodiment of the invention, Figure I, is a vertical section through a part of the vending machine, having my means applied thereto, the vending apparatus being shown in side elevation.

Fig. II, is a detail in plan showing the 40 manually controlled operating members and the coin controlled mechanism which is associated therewith.

Fig. III, is a view similar to Fig. II, showing the part in position for vending the 45 liquid.

Fig. IV, is a detail in vertical section through the storage receptacle and the measuring compartment.

Fig. V, is a detail in vertical section 50 through coin controlled devices with the parts in initial position.

Fig. VI, is a similar view showing the coin moved from initial position, preparatory to the releasing of the coin.

55 Fig. VII, is a transverse section on the

line VII—VII of Fig. I, viewed in the direction of the arrows.

Fig. VIII, is a transverse section on the line VIII—VIII, of Fig. I, viewed in the direction of the arrows.

In carrying out the invention I have provided a main supporting case 1, in which is suitably mounted a storage receptacle 2, for containing the liquid to be vended. This storage receptacle is formed with an opening 3, in the bottom thereof; and a pipe 4, connected with the receptacle at said opening 3, leads to a valve chamber 5, in which is located a valve 6. On the underside of the receptacle 2, is a measuring compartment 7. A short pipe 8, connected with an opening in the lower face of the measuring compartment, leads to the valve chamber 5. A vent pipe 9, leads from the measuring compartment 7, up through the receptacle 2, which permits the liquid to flow from the receptacle into the measuring compartment, when the valve 6, is positioned as shown in Fig. IV. The valve 6, is formed with an opening 10, and an opening 11. It will readily be seen that when the valve 6, is turned, the opening 11, may be brought into register with the pipe 8, and the valve would thereby close the pipe 4. When the valve is thus positioned the opening 10, will be in communication with the pipe 12, and the contents of the measuring compartment may pass through the valve into the pipe 12, the vent pipe 9, permitting said measuring compartment to be emptied. A return of the 90 valve to the position shown in Fig. IV, permits the liquid to run into the measuring compartment, and to fill the same, the vent pipe 9, allowing the air to be forced from said measuring compartment.

The pipe 12, shown in Fig. I extends to the front side of the casing, and leads through the same, and a vending faucet 13, is attached to the end of the pipe. This vending faucet is preferably provided with 100 a valve which is controlled by a handle 14. The valve 6, is provided with an operating wheel 15. A chain 16, is attached to the wheel and extends in both directions therefrom. One end of the chain 16, is attached to a spring 17, which operates to normally hold the valve in a position shown in Fig. I. The other end of the chain is attached to a carriage 18. This carriage 18, is composed of spaced bars 19, 19, which slide in 110

suitable ways formed in a supporting bracket 20 attached to the case 1. This carriage 18, between its ends is provided with a yoke 27, which projects underneath a supporting plate 22, which is secured to the bracket 20. Above said supporting plate and fixed to the bracket 20, is a second slotted plate 23. The forward end of the carriage 18, is provided with a cross bar 24, which extends between the plate 22, and the plate 23. A coin resting on the plate 22, and lying in the slot of plate 23, will engage behind the cross bar 24, and a movement of the coin longitudinally of the plate 22, will 10 move the carriage 18. A coin chute 25, is attached to the case 1, and is so positioned as to drop the coin edgewise into the slot in the plate 23, on to the supporting plate 22. The upper face of the plate 23, is inclined 20 toward the slot so as to facilitate the passing of the coin through the slot. The plate 22, is also formed with guide members 26, 26, between which the coin rolls or slides as it is moved along the plate 22, and the adjacent faces of these guide members are inclined outwardly toward the upper edges of the plates to facilitate the dropping of the coin into the space between the plates.

The plate 22, at its forward end is formed 30 with a slot which registers with the coin chute 41, so that when the coin is brought to a point over the chute 41, it will drop through the slot in the plate. On the under face of the yoke 27, is a roller or stud 28. 35 Mounted on the stem of the valve controlled by the handle 14, is an operating arm 29. This arm 29, is carried by a supporting plate 30, fixed to the stem of the valve, so that when the valve handle 14, is turned, the 40 plate will move therewith, swinging the arm 29. This arm is formed with an inner curved face, and the length of the arm is such that if the handle of the valve 14, is turned, so as to swing the arm, said arm 45 will normally pass by the roller or stud 28, without engaging the same.

The coin effects a movement of the carriage 18, which brings the roller or stud 28, into the path of movement of the arm 29. 50 This is accomplished by a second sliding carriage 31, which is mounted to slide on the plate 23. Said carriage is formed with downwardly and inwardly projecting members 32, 32, which engage the side edges of 55 the plate, so that the carriage slides along the same. Said carriage is provided with a roller or stud 33, which lies in the path of movement of a curved arm 34, also carried by the plate 30. This carriage 31, is 60 provided with an upwardly curved plate 35, which at its upper end is bent backwardly and lies in a horizontal plane as at 36. This plate is so shaped that the horizontal portion 36, thereof passes underneath the end 65 of the coin chute 25, and effects a closing

of the coin chute when the carriage is moved forward for bringing about a vending of the liquid. When a suitable coin is dropped into the coin chute 25, it will pass through the same on to the supporting plate 22. A 70 swinging of the handle 14, which opens the valve at the forward end of the vending pipe, will cause the curved arm 34, to engage the roller 33, thus moving the carriage 31 forward, which engages the coin indicated 75 at 37, in Figs. V to VIII inclusive, and this movement of the carriage 31, will cause the coin to engage the cross bar 24, of the carriage 18, and move this carriage forward until the roller or stud 28, is brought to a 80 point where it will be engaged with the arm 29. A further movement of the handle 14, will cause the carriage 18, to be moved away from the coin slightly by reason of the curvature of the arm 29, and this releases the 85 coin from any clamping or wedging action, so that as the carriage 31, moves to the forward end of its stroke, the coin will be rolled along the plate 22, and dropped through the slot therein into the chute 41. 90 The carriage 31, is retracted by a spring 38, which is attached to a chain 39, running over a roller 40, and the upper end of the chain is attached to the carriage 31. From the above description it will be apparent 95 that the coin is utilized for moving the carriage connected with the valve that controls the measuring compartment, so as to bring said carriage into operative connection with the manually moved arm, and the further 100 movement of the valve is accomplished by the swinging of this arm. Upon the releasing of the handle 14, of the outer valve, the springs 17, and 18, will cause the carriages to be retracted, thus closing the valve 6, and 105 allowing the measuring compartment to be again filled with liquid for vending. If a second coin is dropped into the machine when the carriages are forward and the valve open for vending the liquid, this coin 110 will rest on the plate 36, until the carriages are fully retracted, after which it will drop into position for coupling up the parts for the next releasing of the vending mechanism.

It will be understood that suitable mechanism is provided for the preventing of the insertion of an improper coin into the coin chute 25.

It is obvious that minor changes in the 120 details of construction and arrangement of parts may be made without departing from the spirit of the invention as set forth in the appended claims.

Having thus described my invention, I 125 claim:

1. A coin controlled device including in combination, a reciprocating member, a manually operated arm, said reciprocating member being normally out of the path of 130

movement of said arm, a second reciprocating member, manually controlled means for reciprocating said second member, and devices whereby a coin may be engaged by 5 said second reciprocating member and move said first reciprocating member so as to bring the same into the path of the manually controlled arm.

2. A coin controlled device including in 10 combination, a reciprocating carriage, a manually operated plate, a curved arm carried thereby, a roller mounted on said carriage and normally out of the path of movement of said curved arm, a second carriage, 15 a roller carried thereby, a second curved arm connected to said plate for engaging said roller on said second carriage, and devices whereby a coin may be engaged by said second-named carriage and move said first-named carriage so that the roller carried thereby is brought into the path of movement of the first-named curved arm carried 20 by said manually operated plate.

3. A coin controlled device including in 25 combination, a reciprocating carriage, a manually operated plate, a curved arm carried thereby, a roller mounted on said carriage and normally out of the path of movement of said curved arm, a second carriage, 30 a roller carried thereby, a second curved arm connected to said plate for engaging said roller on said second carriage, and devices whereby a coin may be engaged by said second-named carriage and move said first-named carriage so that the roller carried 35 thereby is brought into the path of movement of the first-named curved arm carried by said manually operated plate, and springs for returning said carriages to their normal 40 positions when the manually operated plate is released.

4. A coin controlled device including in 45 combination, a reciprocating carriage, a second reciprocating carriage, a coin chute, supporting plates for the coin for supporting a coin between said carriages whereby a movement of the last-named carriage will move the first-named carriage, a swinging plate, curved arms carried thereby, a device 50 on the second carriage adapted to be engaged by one of said curved arms, a device on the first carriage adapted to be actuated

by the other curved arm only when said first-named carriage is moved forward through the action of the coin, and means 55 whereby the coin may be discharged from said plate when the first-named carriage is connected with its operating arm.

5. A coin controlled device including in combination, a reciprocating carriage, a second reciprocating carriage, a coin chute, supporting plates for the coin for supporting a coin between said carriages whereby a movement of the last-named carriage will move the first-named carriage, a swinging 60 plate, curved arms carried thereby, a device on the second carriage adapted to be engaged by one of said curved arms, a device on the first carriage adapted to be actuated by the other curved arm only when said 65 first-named carriage is moved forward through the action of the coin, and means whereby the coin may be discharged from said plate when the first-named carriage is connected with its operating arm, and 70 springs for returning said carriages to their 75 normal positions.

6. A coin controlled device including in combination, a reciprocating carriage, a second reciprocating carriage, a coin chute, supporting plates for the coin for supporting a coin between said carriages whereby a movement of the last-named carriage will move the first-named carriage, a swinging plate, curved arms carried thereby, a device 80 on the second carriage adapted to be engaged by one of said curved arms, a device on the first carriage adapted to be actuated by the other curved arm only when said first-named carriage is moved forward 85 through the action of the coin, and means whereby the coin may be discharged from said plate when the first-named carriage is connected with its operating arm, and a supporting plate carried by said second carriage for closing the coin chute when the 90 carriages are moved forward.

In testimony whereof, I have hereunto signed my name at Philadelphia, Pennsylvania, this tenth day of April 1913.

OTTO JAEGER.
